(57) **ABSTRACT**

A cannabis storage assembly for storing objects related to cannabis consumption and playing music includes a box that has a pair of drawers each slidably integrated into the box and a lid hingedly coupled to the box for opening and closing the box. An audio unit is integrated into the lid and the audio unit emits audible sounds when the audio unit is turned on. A set of first light emitters is each integrated into the lid and each of the first light emitters is oriented to emit light upwardly from the lid. A set of second light emitters is each integrated into the lid and each of the second light emitters is oriented to emit light downwardly from the lid.

BACKGROUND OF THE INVENTION

(1) Field of the Invention

The disclosure relates to storage devices and more particularly pertains to a new storage device for storing objects relating to *cannabis* consumption and playing music. The device includes a box with a pair of drawers for storing *cannabis* products and *cannabis* accessories. The device includes an audio unit integrated into the box that can stream audio from a personal electronic device or other audio source.

(2) Description of Related Art Including Information Disclosed Under 37 CFR 1.97 and 1.98

The prior art relates to storage devices including a smoking accessory kit that includes a tray, a plurality of magnets attached to the tray and a plurality of magnetic attachments that can engage the magnets. The prior art discloses a fishing tackle box device that includes light emitting diodes, solar panels and a battery for charging a smart phone. The prior art discloses a *cannabis* management device that includes a *cannabis* grinder, a lighter and a pipe integrated into a case. The prior art discloses a speaker system that is mountable to a utility bag. The prior art discloses a smoker's kit that includes a container and a plurality of tools contained in the container relating to smoking tobacco. The prior art discloses a rolling box device that includes a box with a rolling surface for rolling a cigarette and a plurality of light emitters integrated into the box.

BRIEF SUMMARY OF THE INVENTION

An embodiment of the disclosure meets the needs presented above by generally comprising a box that has a pair

2

of drawers each slidably integrated into the box and a lid hingedly coupled to the box for opening and closing the box. An audio unit is integrated into the lid and the audio unit emits audible sounds when the audio unit is turned on. A set of first light emitters is each integrated into the lid and each of the first light emitters is oriented to emit light upwardly from the lid. A set of second light emitters is each integrated into the lid and each of the second light emitters is oriented to emit light downwardly from the lid.

10 There has thus been outlined, rather broadly, the more important features of the disclosure in order that the detailed description thereof that follows may be better understood, and in order that the present contribution to the art may be better appreciated. There are additional features of the disclosure that will be described hereinafter and which will form the subject matter of the claims appended hereto.

15 The objects of the disclosure, along with the various features of novelty which characterize the disclosure, are 20 pointed out with particularity in the claims annexed to and forming a part of this disclosure.

BRIEF DESCRIPTION OF SEVERAL VIEWS OF THE DRAWING(S)

25 The disclosure will be better understood and objects other than those set forth above will become apparent when consideration is given to the following detailed description thereof. Such description makes reference to the annexed drawings wherein:

30 FIG. 1 is a front perspective view of a *cannabis* storage assembly according to an embodiment of the disclosure.

FIG. 2 is a perspective view of a pair of drawers of an embodiment of the disclosure.

35 FIG. 3 is a perspective view of an embodiment of the disclosure.

FIG. 4 is a schematic view of an embodiment of the disclosure.

30 FIG. 5 is a cross sectional view taken from line 5-5 of FIG. 1 of an embodiment of the disclosure.

DETAILED DESCRIPTION OF THE INVENTION

45 With reference now to the drawings, and in particular to FIGS. 1 through 5 thereof, a new storage device embodying the principles and concepts of an embodiment of the disclosure and generally designated by the reference numeral 10 will be described.

50 As best illustrated in FIGS. 1 through 5, the *cannabis* storage assembly 10 generally comprises a box 12 that has a pair of drawers 14 each is slidably integrated into the box 12, and the box 12 has a bottom wall 16 and a perimeter wall 18 extending upwardly from the bottom wall 16. The

55 perimeter wall 18 has a top edge 20 defining an opening 22 into the box 12, and the perimeter wall 18 has a front side 24, a back side 26, a first lateral side 28 and a second lateral side 30. The box 12 has a dividing wall 32 that is positioned between the bottom wall 16 and the top edge 20. The dividing wall 32 defines a drawer space 34 extending between the dividing wall 32 and the bottom wall 16, and the dividing wall 32 defines a storage space 36 between the dividing wall 32 and the top edge 20.

60 The front side 24 of the perimeter wall 18 has a drawer opening 38 extending into the drawer space 34. The drawer opening 38 is elongated to extend across a substantial width of the front side 24. Additionally, the perimeter wall 18 has

an outer surface **40** and indicia **42** are printed on the outer surface **40**. The indicia **42** comprise images of *cannabis* leaves in various sizes.

A lid **44** is hingedly coupled to the box **12** for opening and closing the box **12**. The lid **44** has a top wall **46** and an outer wall **48** extending downwardly from the top wall **46**, and the outer wall **48** has a bottom edge **50**, a forward side **52** and a rear side **54**. The bottom edge **50** corresponding to the rear side **54** is hingedly coupled to the top edge of the perimeter wall **18** of the box **12** corresponding to the back side **26** of the perimeter wall **18**. Furthermore, the bottom edge **50** lies on the top edge **20** when the lid **44** is closed. A strap **56** is provided which has a first end **58** and a second end **60**, and the strap **56** a pair of pivot points **62** each located adjacent to a respective first end **58** and second end **60**. Each of the pivot points **62** is pivotally coupled to a respective first lateral side **28** and second lateral side **30** of the perimeter wall **18** of the box **12** such that the strap **56** forms a loop for carrying the box **12**.

The pair of drawers **14** includes a first drawer **64** is slidably integrated into the box **12** for storing objects commonly associated with *cannabis* consumption. The first drawer **64** has a pair of dividers **66** that are perpendicularly oriented with each other to define a plurality of storage spaces **68** in the first drawer **64**. The first drawer **64** has a front wall **70** and the first drawer **64** has a handle **72** which is attached to the front wall **70**. The first drawer **64** is slidably positioned in the drawer opening **38** in the front side **24** of the perimeter wall **18** of the box **12**, and the front wall **70** is oriented flush with the front side **24** when the first drawer **64** is closed.

The pair of drawers **14** includes a second drawer **74** that is slidably integrated into the box **12** for storing objects commonly associated with *cannabis* consumption. The second drawer **74** has a forward wall **76** and the second drawer **74** has a handle **78** that is attached to the forward wall **76**. The second drawer **74** is slidably positioned in the drawer opening **38** in the front side **24** of the perimeter wall **18** of the box **12** and the forward wall **76** is oriented flush with the front side **24** when the second drawer **74** is closed. Furthermore, the second drawer **74** is positioned on top of the first drawer **64**. A rolling tray **80** is positionable on the second drawer **74** for storing the rolling tray **80** and the rolling tray **80** is removable from the second drawer **74**. The rolling tray **80** has a perimeter wall **82** angling upwardly from a basal wall **84** such that the perimeter wall **82** of the rolling tray **80** inhibits *cannabis* placed on the rolling tray **80** from spilling off of the rolling tray **80**.

A latch **86** is hingedly coupled to the forward side **52** of the outer wall **48** of the lid **44**. An engagement **88** is attached to the front side **24** of the perimeter wall **18** of the box **12**. The latch **86** engages the engagement **88** when the latch **86** is in a closed position for retaining the lid **44** in a closed position. Additionally, a cotter pin **90** is extendable through a catch **92** on the latch **86** and the engagement **88** for retaining the latch **86** in the closed position.

An audio unit **94** is integrated into the lid **44** and the audio unit **94** emits audible sounds when the audio unit **94** is turned on. The audio unit **94** comprises a control circuit **96** that is integrated into the lid **44** and the audio unit **94** includes a display **98** that is integrated into the forward side **52** of the outer wall **48** of the lid **44**. The display **98** is electrically coupled to the control circuit **96** and the display **98** displays indicia **100** comprising operational parameters of the audio unit **94**. The audio unit **94** includes a speaker **102** that is integrated into the top wall **46** of the lid **44** such

that the speaker **102** emits audible sounds outwardly from the top wall **46** and the speaker **102** is electrically coupled to the control circuit **96**.

The audio unit **94** includes a transceiver **104** that is integrated into the lid **44** and the transceiver **104** is electrically coupled to the control circuit **96**. The transceiver **104** is in wireless communication with an audio source **106** thereby facilitating the speaker **102** to receive an audio signal from the audio source **106**. The transceiver **104** may comprise a radio frequency transceiver or the like and the transceiver **104** may employ Bluetooth communication protocols. Additionally, the audio source **106** may comprise a smart phone or other similar electronic source of digital streaming media.

The audio unit **94** includes a volume control **108** which is integrated into the forward side **52** of the outer wall **48** of the lid **44**. The volume control **108** is electrically coupled to the control circuit **96** and the volume control **108** adjusts a volume of the speaker **102** between a minimum volume and a maximum volume. The audio unit **94** includes an input port **110** that is recessed into the forward side **52** of the perimeter wall **18** of the lid **44** thereby facilitating the input port **110** to receive an audio cord **112**. The input port **110** is electrically coupled to the control circuit **96** thereby facilitating the speaker **102** to receive an audio signal from the audio cord **112**. Additionally, the input port **110** may be a quarter inch stereo jack or other similar audio input port. The audio unit **94** includes an audio selection switch **114** that is movably integrated into the forward side **52** of the outer wall **48** of the lid **44**. The audio selection switch **114** is electrically coupled to the control circuit **96** and the audio selection switch **114** selects either the input port **110** or the transceiver **104** as an audio source **106** for the speaker **102**.

The audio unit **94** includes a power supply **116** that is integrated into the lid **44** and the power supply **116** is electrically coupled to the control circuit **96**. The power supply **116** comprises a rechargeable battery **118** that is integrated into the lid **44** and the rechargeable battery **118** is electrically coupled to the control circuit **96**. The power supply **116** includes a first charge port **120** that is recessed into the perimeter wall **18** of the lid **44** thereby facilitating the first charge port **120** to insertably receive a charge cord **122**. Additionally, the first charge port **120** is electrically coupled to the rechargeable battery **118** for charging the rechargeable battery **118**.

The power supply **116** includes a second charge port **124** that is recessed into the outer wall **48** of the lid **44** thereby facilitating the second charge port **124** to insertably receive a power cord for an electronic device. The second charge port **124** is electrically coupled to the rechargeable battery **118** for charging the electronic device with the rechargeable battery **118**. The power supply **116** includes a power switch **126** that is movably integrated into the forward side **52** of the outer wall **48** of the lid **44**, the power switch **126** is electrically coupled to the control circuit **96** and the power switch **126** turns the control circuit **96** on and off.

A set of first light emitters **128** is each integrated into the lid **44** and each of the first light emitters **128** is oriented to emit light upwardly from the lid **44**. Each of the first light emitters **128** is positioned on a top surface **130** of the top wall **46** of the lid **44** and each of the first light emitters **128** is electrically coupled to the control circuit **96**. Additionally, each of the first light emitters **128** may comprise a light emitting diode or other type of electronic light emitter.

A set of second light emitters **132** is each integrated into the lid **44** and each of the second light emitters **132** is oriented to emit light downwardly from the lid **44**. Each of

the second light emitters 132 is positioned on a bottom surface 134 of the top wall 46 of the lid 44 and the set of second light emitters 132 is arranged into a pair of rows 136 extending laterally across the bottom surface 134. Each of the second light emitters 132 is electrically coupled to the control circuit 96 and each of the second light emitters 132 may comprise a light emitting diode or the like.

In use, various objects related to the consumption of *cannabis* are stored in the box 12 as well as in the first drawer 64 and the second drawer 74. The rolling tray 80 can be taken out of the second drawer 74 for rolling *cannabis* cigarettes, for example. Additionally, audio can be played with the audio unit 94 from either a wireless source or a wired source. In this way the box 12 and the audio unit 94 facilitate *cannabis* to be consumed along with the ability to listen to music.

With respect to the above description then, it is to be realized that the optimum dimensional relationships for the parts of an embodiment enabled by the disclosure, to include variations in size, materials, shape, form, function and manner of operation, assembly and use, are deemed readily apparent and obvious to one skilled in the art, and all equivalent relationships to those illustrated in the drawings and described in the specification are intended to be encompassed by an embodiment of the disclosure.

Therefore, the foregoing is considered as illustrative only of the principles of the disclosure. Further, since numerous modifications and changes will readily occur to those skilled in the art, it is not desired to limit the disclosure to the exact construction and operation shown and described, and accordingly, all suitable modifications and equivalents may be resorted to, falling within the scope of the disclosure. In this patent document, the word "comprising" is used in its non-limiting sense to mean that items following the word are included, but items not specifically mentioned are not excluded. A reference to an element by the indefinite article "a" does not exclude the possibility that more than one of the element is present, unless the context clearly requires that there be only one of the elements.

I claim:

1. A *cannabis* storage assembly for storing products and tools associated with *cannabis* consumption, said assembly comprising:

a box having a pair of drawers each being slidably integrated into said box;

a lid being hingedly coupled to said box for opening and closing said box;

an audio unit being integrated into said lid, said audio unit emitting audible sounds when said audio unit is turned on;

a set of first light emitters, each of said first light emitters being integrated into said lid, each of said first light emitters being oriented to emit light upwardly from said lid;

a set of second light emitters, each of said second light emitters being integrated into said lid, each of said second light emitters being oriented to emit light downwardly from said lid;

wherein said box has a bottom wall and a perimeter wall extending upwardly from said bottom wall, said perimeter wall having a top edge defining an opening into said box, said perimeter wall having a front side, a back side, a first lateral side and a second lateral side;

wherein said box has a dividing wall being positioned between said bottom wall and said top edge, said dividing wall defining a drawer space extending between said dividing wall and said bottom wall, said

dividing wall defining a storage space between said dividing wall and said top edge;

wherein said front side of said perimeter wall has a drawer opening extending into said drawer space, said drawer opening being elongated to extend across a substantial width of said front side; and

wherein said perimeter wall has an outer surface, said outer surface having indicia being printed thereon, said indicia comprising images of *cannabis* leaves; and said lid has a top wall and an outer wall extending downwardly from said top wall, said outer wall having a bottom edge, a forward side and a rear side, said bottom edge corresponding to said rear side being hingedly coupled to said top edge of said perimeter wall of said box corresponding to said back side of said perimeter wall, said bottom edge lying on said top edge when said lid is closed.

2. The assembly according to claim 1, wherein said pair of drawers includes a first drawer being slidably integrated into said box for storing objects commonly associated with *cannabis* consumption, said first drawer having a pair of dividers being perpendicularly oriented with each other to define a plurality storage spaces in said first drawer, said first drawer having a front wall, said first drawer having a handle being attached to said front wall, said first drawer being slidably positioned in said drawer opening in said front side of said perimeter wall of said box, said front wall being oriented flush with said front side when said first drawer is closed.

3. The assembly according to claim 2, wherein:

said pair of drawers includes a second drawer being slidably integrated into said box for storing objects commonly associated with *cannabis* consumption, said second drawer having a forward wall, said second drawer having a handle being attached to said forward wall, said second drawer being slidably positioned in said drawer opening in said front side of said perimeter wall of said box, said forward wall being oriented flush with said front side when said second drawer is closed, said second drawer being positioned on top of said first drawer; and

said assembly includes a rolling tray being positionable on said second drawer for storing said rolling tray, said rolling tray being removably from said second drawer, said rolling tray having a perimeter wall angling upwardly from a basal wall such that said perimeter wall of said rolling tray inhibits *cannabis* placed on said rolling tray from spilling off of said rolling tray.

4. The assembly according to claim 1, wherein said audio unit comprises:

a control circuit being integrated into said lid;

a display being integrated into said forward side of said perimeter wall of said lid, said display being electrically coupled to said control circuit, said display displaying indicia comprising operational parameters of said audio unit; and

a speaker being integrated into said top wall of said lid such that said speaker emits audible sounds outwardly from said top wall, said speaker being electrically coupled to said control circuit.

5. The assembly according to claim 4, wherein said audio unit includes:

a transceiver being integrated into said lid, said transceiver being electrically coupled to said control circuit, said transceiver being in wireless communication with an audio source thereby facilitating said speaker to receive an audio signal from the audio source;

a volume control being integrated into said forward side of said perimeter wall of said lid, said volume control being electrically coupled to said control circuit, said volume control adjusting a volume of said speaker between a minimum volume and a maximum volume; 5 an input port being recessed into said forward side of said perimeter wall of said lid thereby facilitating said input port to receive an audio cord, said input port being electrically coupled to said control circuit thereby facilitating said speaker to receive an audio signal from 10 the audio cord; and an audio selection switch being movably integrated into said forward side of said perimeter wall of said lid, said audio selection switch being electrically coupled to said control circuit, said audio selection switch selecting either said input port or said transceiver as an audio 15 source for said speaker.

6. The assembly according to claim 4, further comprising a power supply being integrated into said lid, said power supply being electrically coupled to said control circuit, said 20 power supply comprising:

a rechargeable battery being integrated into said lid, said rechargeable battery being electrically coupled to said control circuit; a first charge port being recessed into said perimeter wall 25 of said lid thereby facilitating said first charge port to insertably receive a charge cord, said first charge port being electrically coupled to said rechargeable battery for charging said rechargeable battery; a second charge port being recessed into said perimeter 30 wall of said lid thereby facilitating said second charge port to insertably receive a power cord for an electronic device, said second charge port being electrically coupled to said rechargeable battery for charging the electronic device with said rechargeable battery; and a power switch being movably integrated into said forward side of said perimeter wall of said lid, said power 35 switch being electrically coupled to said control circuit, said power switch turning said control circuit on and off.

7. The assembly according to claim 4, wherein each of 40 said first light emitters is positioned on a top surface of said top wall of said lid, each of said first light emitters being electrically coupled to said control circuit.

8. The assembly according to claim 4, wherein each of 45 said second light emitters is positioned on a bottom surface of said top wall of said lid, said set of second light emitters being arranged into a pair of rows extending laterally across said bottom surface, each of said second light emitters being electrically coupled to said control circuit.

9. A *cannabis* storage assembly for storing products and tools associated with *cannabis* consumption, said assembly 50 comprising:

a box having a pair of drawers each being slidably integrated into said box, said box having a bottom wall 55 and a perimeter wall extending upwardly from said bottom wall, said perimeter wall having a top edge defining an opening into said box, said perimeter wall having a front side, a back side, a first lateral side and a second lateral side, said box having a dividing wall 60 being positioned between said bottom wall and said top edge, said dividing wall defining a drawer space extending between said dividing wall and said bottom wall, said dividing wall defining a storage space between said dividing wall and said top edge, said front 65 side of said perimeter wall having a drawer opening extending into said drawer space, said drawer opening

being elongated to extend across a substantial width of said front side, said perimeter wall having an outer surface, said outer surface having indicia being printed thereon, said indicia comprising images of *cannabis* leaves;

a lid being hingedly coupled to said box for opening and closing said box, said lid having a top wall and an outer wall extending downwardly from said top wall, said outer wall having a bottom edge, a forward side and a rear side, said bottom edge corresponding to said rear side being hingedly coupled to said top edge of said perimeter wall of said box corresponding to said back side of said perimeter wall, said bottom edge lying on said top edge when said lid is closed;

wherein said pair of drawers includes a first drawer being slidably integrated into said box for storing objects commonly associated with *cannabis* consumption, said first drawer having a pair of dividers being perpendicularly oriented with each other to define a plurality of storage spaces in said first drawer, said first drawer having a front wall, said first drawer having a handle being attached to said front wall, said first drawer being slidably positioned in said drawer opening in said front side of said perimeter wall of said box, said front wall being oriented flush with said front side when said first drawer is closed;

wherein said pair of drawers includes a second drawer being slidably integrated into said box for storing objects commonly associated with *cannabis* consumption, said second drawer having a forward wall, said second drawer having a handle being attached to said forward wall, said second drawer being slidably positioned in said drawer opening in said front side of said perimeter wall of said box, said forward wall being oriented flush with said front side when said second drawer is closed, said second drawer being positioned on top of said first drawer;

a rolling tray being positionable on said second drawer for storing said rolling tray, said rolling tray being removably from said second drawer, said rolling tray having a perimeter wall angling upwardly from a basal wall such that said perimeter wall of said rolling tray inhibits *cannabis* placed on said rolling tray from spilling off of said rolling tray;

an audio unit being integrated into said lid, said audio unit emitting audible sounds when said audio unit is turned on, said audio unit comprising:

a control circuit being integrated into said lid; a display being integrated into said forward side of said perimeter wall of said lid, said display being electrically coupled to said control circuit, said display displaying indicia comprising operational parameters of said audio unit;

a speaker being integrated into said top wall of said lid such that said speaker emits audible sounds outwardly from said top wall, said speaker being electrically coupled to said control circuit;

a transceiver being integrated into said lid, said transceiver being electrically coupled to said control circuit, said transceiver being in wireless communication with an audio source thereby facilitating said speaker to receive an audio signal from the audio source;

a volume control being integrated into said forward side of said perimeter wall of said lid, said volume control being electrically coupled to said control

9

circuit, said volume control adjusting a volume of said speaker between a minimum volume and a maximum volume; an input port being recessed into said forward side of said perimeter wall of said lid thereby facilitating said input port to receive an audio cord, said input port being electrically coupled to said control circuit thereby facilitating said speaker to receive an audio signal from the audio cord; an audio selection switch being movably integrated into said forward side of said perimeter wall of said lid, said audio selection switch being electrically coupled to said control circuit, said audio selection switch selecting either said input port or said transceiver as an audio source for said speaker; and a power supply being integrated into said lid, said power supply being electrically coupled to said control circuit, said power supply comprising: a rechargeable battery being integrated into said lid, said rechargeable battery being electrically coupled to said control circuit; a first charge port being recessed into said perimeter wall of said lid thereby facilitating said first charge port to insertably receive a charge cord, said first charge port being electrically coupled to said rechargeable battery for charging said rechargeable battery; a second charge port being recessed into said perimeter wall of said lid thereby facilitating said sec-

10

ond charge port to insertably receive a power cord for an electronic device, said second charge port being electrically coupled to said rechargeable battery for charging the electronic device with said rechargeable battery; and a power switch being movably integrated into said forward side of said perimeter wall of said lid, said power switch being electrically coupled to said control circuit, said power switch turning said control circuit on and off; and a set of first light emitters, each of said first light emitters being integrated into said lid, each of said first light emitters being oriented to emit light upwardly from said lid, each of said first light emitters being positioned on a top surface of said top wall of said lid, each of said first light emitters being electrically coupled to said control circuit; and a set of second light emitters, each of said second light emitters being integrated into said lid, each of said second light emitters being oriented to emit light downwardly from said lid, each of said second light emitters being positioned on a bottom surface of said top wall of said lid, said set of second light emitters being arranged into a pair of rows extending laterally across said bottom surface, each of said second light emitters being electrically coupled to said control circuit.

* * * * *
